UNITED STATES PATENT OFFICE

MARTIN J. LIDE, OF BIRMINGHAM, ALABAMA

DRY SEPARATOR

Application filed December 16, 1926. Serial No. 155,259.

My invention relates to dry separators or shaking screens adapted to effect a stratification and separation, according to specific gravities, of the component parts of a charge of material thereon, and it contemplates that the material shall be continuously fed to the separator and that the separating table shall have imparted thereto both vertical vibrations and lateral oscillations and shall have a 10 foraminous deck so that a current of air can be forced upwardly through the mass of material on the table.

The chief object of my present invention is to maintain upon the separating table one 15 or more deep beds of material each in a separate compartment, and to provide for the overflow of the light material over one edge of a compartment and the underflow of the heavy material under another edge of said compartment. Where multiple compartments are used, the light material may be 20 caused to overflow from one into the next compartment for successive treatments while the heavy material passes directly to the discharge or vice versa.

My invention contemplates the control of the discharge of heavy material from each compartment by causing it to pass out under a gate preferably adjustable so that the depth 25 of the heavy material in each compartment bed can be so regulated as to prevent the escape of lighter material therefrom under its respective gate.

My invention contemplates that the lighter material shall travel in one direction and the heavy material in a direction at or nearly at right angles to the direction of flow of the lighter material, and where it is desired to use riffles on the table, such should be arranged parallel with the weirs. Also, where 35 it is desired to incline the table in the direction of the discharge of the heavy material, it is preferable that the weirs should be adjustable angularly so as to permit of raising 40 the edges thereof adjacent to the discharge of the heavy material. By thus maintaining a deep bed of material in each compartment of a table that is being both vertically vibrated and laterally oscillated, the most effective stratification as well as the desired

rate of movement of the material is obtained, the heavier material from each compartment underflowing a gate in one direction to its respective discharge or into the next succeeding compartment, and the lighter material in each compartment overflowing a weir in a different direction in the next succeeding compartment or into the discharge. By the adjustment of the gates ample depth of heavy material can be maintained in the beds so 55 that there will be a substantially uniform distribution of the air current flowing upwardly through the material. Moreover, the increased depth of the beds increases the depth 60 of the zone of stratification and therefore enables the line of demarkation between the lighter and heavier material to be more clearly defined.

A further feature of this invention relates 65 to the manner in which the vertical vibrations are imparted to the table, this being accomplished, according to my present invention, by the provision of synchronized crank actuators for the adjustable table supporting legs.

My invention further contemplates improvements in the manner in which the gates and weirs are mounted and adjusted on the 70 table.

My invention in several preferred embodiments thereof is illustrated in the accompanying drawings to which reference is had in the following specification and claim.

In the drawings:—

Fig. 1 is a plan view of a separating table 75 with the cover partly broken away.

Fig. 2 is an end elevation of Fig. 1 partly broken away, with the air circuit conventionally illustrated.

Fig. 3 is a partial sectional view enlarged 80 taken along the line III—III of Fig. 1.

Fig. 4 is a detail view illustrating the angular and vertical adjustability of the weirs.

Fig. 5 is a cross-sectional view taken on the 85 lines V—V of Fig. 2.

Fig. 6 is a side elevation of Fig. 1 partly broken away.

Figs. 7 and 8 are views corresponding to Figs. 1 and 2 of a modification of my invention in which overhead adjustable baffles are 90

arranged at right angles to the riffles and take the place of the weirs which run parallel with the riffles in Figs. 1 to 2.

Fig. 9 is a side view partly broken away, 5 of Fig. 7.

Fig. 10 is an enlarged sectional view taken on the line X—X of Fig. 7 with the adjustable vibrating supports for the table shown partly in cross-section.

10 Fig. 11 is a detailed view of one of the vibratory table supports.

Fig. 12 is an enlarged sectional view taken on the line XII—XII of Fig. 7.

15 Fig. 13 is an enlarged detail view showing the double screen arrangement and manner of supporting the upper screen and riffles on the lower screen.

20 Fig. 14 is a detail view showing the adjustable mounting for the overhead baffles of Fig. 7.

Similar reference numerals refer to similar parts throughout the drawings.

In the several embodiments of my invention illustrated, I show an air box 15 having a plurality of flexible air ducts 16 which connect the same with inlets 17 in the bottom 18 of the separator proper, which bottom is surrounded by marginal vertical walls 19, 20, 21 and 22. Suitably spaced from the bottom 30 and mounted on cross division plates 23 by angle clips 23a are inner screen plates 24 having relatively large perforations, and above screens 24 is supported thereon a working screen 25 having finer perforations 26 (see 35 Fig. 13), upon which screen is mounted the riffles 27, when such are used, and I preferably form them of angle irons or other suitable material. The riffles are shown as alternately high and low but they may be of any standard type.

The manner of assembling the screens and riffles is preferably according to the showing in Fig. 13 in which a cap screw or stud bolt 28 is passed down through the base flange of 45 a riffle angle 27 and through the upper screen 25 and through a spacer sleeve 29 resting on the screen 24, and is screwed into the latter screen, the riffles not in position to be mounted by cap screws 28 may be attached to the 50 upper screen 25 in any suitable manner. Suitable control valves 30 are provided in the connections leading from the air box 15 to each duct 16 to regulate the volume of air delivered through same to the screen. The 55 division plates 23 are adapted to subdivide the air chamber below the screens into compartments into each of which an equal number of air ducts 16 lead from the air box 15 so as to regulate the volume of air supplied .0 to each compartment.

The screen mechanism is supported at or near its four corners by adjustable leg supports which are more clearly illustrated in Figs. 6, 10 and 11, each leg preferably comprising an upper threaded member 31 which

is connected by a universal joint coupling 32 to the bottom 18. The threaded member 31 is screwed into the hub 33 of a sprocket 34, which hub in turn is provided with an unthreaded cylindrical shank 35 which turns either in the upper end of a lower elongated hub 36 for a sprocket 37, which has the member 38 screwed into its lower end and connected by a pivot bolt 39 to the sleeve 40 of its respective oscillating eccentric 41 or the shank 35 turns in a sleeve 36a into which the member 38 screws and is set by a jamb nut 36b. These eccentrics are mounted respectively upon the shafts 42, 43 and 44, the shafts 42 and 43 being driven by the bevelled gears 45 which mesh a bevelled pinion 46 on a drive shaft 47 driven by the motor 48, which is typical of any suitable source of power. The shaft 44 is driven by the meshing gears 49 and 50, as more clearly seen in Fig. 5, and each of the shafts is provided with suitable bearings 51 beyond which its ends overhang and receive the eccentrics 41. The connections described provide for independent adjustment of each of the leg supports for the table and for the transmission by the synchronized crank or eccentric means of vertical vibrations through these supports to the table.

To provide for the simultaneous adjustment of the legs on any desired side of the table I connect the upper sprocket wheels 37 on the right hand side of Fig. 5 by means of a sprocket chain 52 and I provide for adjustment of the supports of the upper end of the table, see Fig. 5, by connecting the lower sprocket by means of a sprocket chain 53 both flights of which are passed around the guides 54 to avoid the end ducts 16. Thus by manipulating the chain 52 the right hand side of the table can be raised or lowered without varying its pitch or angle of inclination, and in like manner the upper end of the table can be raised or lowered by manipulating the chain 53 without changing its pitch or angle of inclination.

I attach, preferably at each corner of the table, a stirrup 55 upon which is mounted a coil spring 56 engaged above by a seat 57 (see Fig. 10) through which the upper end of a hold-down rod 58 passes and carries a nut to adjust the tension of the spring which rests on the stirrup and is held under compression by reason of the fact that the lower end of the hold-down rod is loosely connected to an eye 59 in a bracket or base plate secured to the floor or foundation. These hold-downs thus serve, through the interposed springs 56, to yieldingly hold the table against its vertical vibratory driving elements 41 and prevent any knocking or loose motion in the vertical vibratory drive.

By means of a pulley 61 on the motor 48 I drive a belt 62 which transmits motion to a pulley 63 on a shaft 64 mounted in suit-

able bearings 65 on the floor or foundation and having fast at its intermediate point a cam 66, and at its end a bevelled gear 67, meshes with a gear 68 and serves to drive a shaft 69 disposed at right angles to the shaft 64 and having fast thereon a cam 70. The cams 66 and 70 are set opposite the centers of their respective adjacent edges of the separator table and each cam is so shaped that, through suitable transmission mechanism, it is adapted to impart oscillations to the table which will produce a slow motion in one direction and a fast return. As shown, each cam engages a roller 71 mounted in the yoke 15 at the outer end of its connecting rod 72, the yoke serving as an outer seat for a coil compression spring 73 which bears at its other end against a guide 74 through which the connecting rod loosely slides at an upward 20 inclination. These rods, working at right angles to each other are, at their inner ends connected by ball and socket joints 75 to a center thrust plate 76 attached to the bottom 25 of the separator. The cams are designed to impart a relatively slow forward motion and to permit a quick return, and being disposed to work at right angles to each other, the connections and supports are all suited to permit the table to follow its natural movements responsive both to the vertical vibrations and to the different directions for lateral oscillations. The cams are shown provided with side flanges to hold the rollers 71 in alignment therewith. The motion just described may best be understood by reference to Fig. 6 wherein it will be seen that with the cam 66 rotating in an anticlockwise direction the table is moved to the right, as seen in the drawings, and is more quickly 30 returned by the spring 73.

The mechanism described for oscillating the table is of the conventional type and may be variously modified according to different operating conditions, and in like manner there may be substituted for the vertical vibrating mechanism shown other suitable means.

Referring more particularly to Figs. 1 to 6, I illustrate one arrangement of the table in which the material to be treated is fed to the upper left hand corner by means of a feed pipe 77 and in which the riffles are arranged parallel with the end walls 20 and 22. As shown in the figures in question, the screen 25 is made up of sections between which the division plates 23 rise and extend up high enough to form with the marginal walls of the top cover 84 deep compartments from which the lighter material can escape only by overflowing the plates 23 as weirs. Preferably I mount adjustable weir plates 78 on each plate 23, employing screws 88 working in slots 89 to permit the weir plates to be adjusted both vertically and angularly.

The heavier material in each compartment

is discharged at the ends of the riffles by passing under an adjustable bottom-discharge gate 79 and through a chute 80. The gate 79 slides through a slot in the chute and is provided with a top out-turned flange connected by adjusting screws 82 with an angle clip 83 attached to the adjacent side of the top cover 84. The screws 82 have collars to hold them in position on the clip 83 and thus prevent movement of the gate responsive to vertical table vibrations. The table at its discharge edge for the lighter material is provided with an overflow weir 85 and weir plate 78 which rises to the height of the other weir plates and over which the lighter material falls into a hopper 86 having a bottom incline leading to a discharge 87. In this arrangement all of the heavier material is discharged over the right hand edge of the table into the hoppers 81 and all of the lighter material is discharged over the weir 85 into the discharge chute 86, and in reaching the chute 86 the lighter material must pass successively from one compartment to the other and in doing so must find its way over the several weir plates 78. The heavier material that passes one or more of the weir plates 78 tends to move always mostly towards the edge 19 following the riffles and before reaching the weir 85 all the heavier material will have been caught in one or the other of the several compartments and discharged therefrom under its gate 79. It will be apparent that the weirs serve to maintain a deep bed of material being treated over the whole screen surface 25 and that by the adjustment of the gates 79 the rate of outflow of the heavier material can be regulated and controlled so as to maintain it to the desired depth in each compartment.

In Figs. 7 to 10 the separator is arranged to provide for the flow of the heavier material from compartment to compartment, thus successively treating it, while the lighter material overflows directly to the discharge. Here the compartments are defined by the wide overhead angles forming gates 90 which stand parallel with the plates 23 but are spaced so that their bottom edges leave an adjustable clearance under which the heavy material escapes and passes from compartment to compartment, following the riffles 27 to the discharge chutes 91 and 92 or escapes directly to those chutes where a single compartment is provided. The lighter material in this separator travels parallel with the gates and across the riffles and is discharged over the end weir 93 which serves the same function as the weir 85 in the construction first described. In order to adjust this weir 93 I mount it by bolts 94 working in vertical slots in the side 19, and it can thus be adjusted to regulate the depth of the bed of material on the screen.

To mount the angles I cause their ends to

project through the casing of the separator, the horizontal flange of the angle being slotted to permit of its reception in a narrow slot 95 which opens through the top of the 5 vertical side walls 96 of the casing as indicated in Fig. 14. I mount brackets 97 on the casing which project up through end slots 98 in the top flange of the angles 90 and are theraded to receive the hand nuts 99 10 which are circumferentially reduced at 100 to fit the slot 98 and engage both under and over the angle flange so that by turning the nuts 99 the angle gates can be held in any desired adjusted position. In order to permit these gates to be lowered below the riffles, the latter are notched at 101 in line with each gate, see Fig. 12. The air currents flowing upwardly through the screens and the material thereon is caught by the head 20 102 and preferably returned in circuit, through the duct 103 to the air box 15.

The synchronous drive of the crank or eccentric vibrators to the separator legs will maintain the mass of material thereon under 25 constant agitation while the air current divided and distributed through the agencies described will flow up through the agitated material. The table is normally inclined so that the edges over which the material is discharged are lowest. Hence the mass of material will tend to travel towards those edges being assisted by the lateral oscillations imparted to the table both endwise and sidewise. The beds of heavy material will accumulate 30 on the screen in the several compartments, being controlled by the adjustment of the gates 79 or 90 and the lighter material collecting above the beds of heavy material will flow at right angles to the direction of discharge 40 of the heavy material, and can escape from a compartment only by overflowing a weir plate 78 or the discharge weirs 85 or 93. Where riffles are used, they lie in the direction of discharge of the heavy material, and where 45 the table is inclined in the said direction the weirs can be adjusted to maintain their top edges level or rising towards the heavy material discharges, as may be desired. The deep agitated beds of material thus maintained, 50 permit of a clear line of demarkation between the light and heavy material being maintained and enable accurate adjustments to be made of both gates and weirs to secure the most efficient separation. The air current assists in stratification and the deep beds insure a more uniform air flow up through the mass and avoid tendency towards empty or thinly covered parts of the screen, permitting the air current to bypass the mass of material on 55 the bed or causing it to act inefficiently.

Though I have described with great particularity the details of the embodiment of the invention herein shown, it is not to be construed that I am limited thereto, as 60 changes in arrangement and substitution of

equivalents may be made by those skilled in the art without departing from the invention as defined in the appended claim.

Having thus described my invention, what I claim as new and desire to secure by Letters Patent, is:—

In a dry separator, partitions dividing the separator into a succession of deep compartments, means providing an upward flow of air through the several compartments to stratify the material, means to feed material into one of the end compartments of the separator, means to impart horizontal reciprocatory motion to the separator normal to the partitions to cause the lighter components of the material to overflow said partitions successively, concomitant means to impart reciprocatory motion to the separator in a direction parallel to the partitions to effect movement of the heavier components of the material transversely to the lighter material, concomitant means to vertically vibrate the table to aid in stratification of the material, adjustable gates to remove the heavier components of the materials at the side of the separator in each compartment, and riffles provided in the compartments parallel with the partition walls.

In testimony whereof I affix my signature.

MARTIN J. LIDE.
